UNITED STATES PATENT OFFICE

STEPHEN SMITH, OF SAN FRANCISCO, CALIFORNIA

FLAG HOLDER

Application filed January 3, 1928. Serial No. 244,320.

My invention relates to means for securing fabric sheets, such as flags, to suitable staffs or supports. Although my invention is generally applicable, it is particularly adapted 5 to secure flags to staffs as they are used in railroading, and to secure shades to rollers.

An object of my invention is to provide a flag holder which will permit the ready attachment and detachment of a flag.

Another object of my invention is to provide a flag holder which can be used with a succession of flags.

A further object of my invention is to 15 provide a flag holder which will support its associated flag thruout the length thereof.

My invention possesses other advantageous features, some of which with the foregoing will be set forth at length in the following description where I shall outline in full that form of the flag holder of my invention which I have selected for illustration in the drawings accompanying and forming part of the present specification. In said 25 drawings I have shown one form of flag holder embodying my invention, but it is to be understood that I do not limit myself to such form since the invention as set forth in the claims, may be embodied in a plurality of 30 forms.

In the drawings:

Fig. 1 is a side elevation of my flag holder in use, portions being broken away to disclose the construction.

35 Fig. 2 is an enlarged view similar to Fig. 1.

Fig. 3 is a view, similar to Fig. 2, showing the use of the offset in the retainer.

Fig. 4 is a side elevation of my flag holder showing the retainer released.

40 Fig. 5 is a detail of the hook.

In its preferred form, the flag holder of my invention preferably comprises a staff with a resilient retainer secured thereto and tending to diverge therefrom together with 45 means for holding the retainer tightly in contact with the staff.

As mentioned above, the flag holder of my invention is easily adaptable to a variety of uses but it finds an important field in railroading in which signal flags are largely em-

ployed. The flags in use become soiled quickly and for that and other reasons must often be changed. With the present mode of attachment of flags to their staffs it is necessary either to remove the tacks from the staff 55 which hold the flag and subsequently tack a new flag in place on the staff or to dispose of the entire flag and staff as a unit. These methods are slow or costly or both and are fraught with subsidiary disadvantages such as the necessity of repairing flags torn by 60 tacks, cleaning the flags to remove tack rust and of frequently replacing the staffs.

To overcome these disadvantages and to 65 provide a number of advantages over the prior methods of construction, I have preferably provided a staff 6, usually of wood, turned in generally cylindrical form and conveniently provided with a grip 7 at one end thereof. The staff can be treated with suitable weather proofing if desired but such treatment is not deemed essential. To the staff is secured means for retaining a flag. This retainer conveniently takes the form of a continuous rod or wire 8 preferably of 70 spring steel and finished to protect it from rust. As a simple means for securing retainer 8 to the staff 6, I preferably provide one end of the retainer with a reverse bend ending in a barbed tip 9 and which is of 75 such proportions that the barbed tip engages centrally the end of the staff 6.

In order to assure substantially uniform contact with the staff 6 thruout the length of the retainer 8, I preferably form the retainer with a permanent set tending to cause the retainer to diverge from the staff in an arcuate path. This is disclosed in Fig. 4 in which it is seen that the barbed end 9 holds one end of the retainer in close proximity 80 to the staff 6 while the opposite end of the retainer is spaced a considerable distance from the staff.

It is intended that a flag be gripped between the retainer 8 and the staff 6 and while 85 this can be accomplished simply by inserting a flag therebetween, I preferably provide a flag 11 having a hem 12 along one side thereof. The open hem is slipped over the free end of the retainer and the flag is usually dis- 90 100

posed with one margin adjacent the end of the staff.

The flag is clamped firmly between the retainer and the staff when the wire 8 is held against the staff 6. A convenient means for holding the retainer is a hook 13 usually having a barbed point 14 driven into the wood of the staff 6. The free end of the retainer 8 is forced toward the staff and is slipped laterally to lie underneath the hook 13.

To insure that the retainer is always tightly in contact with the staff, I preferably provide adjacent the free end of the wire an offset portion 15 extending away from the staff 6. With this offset portion in contact with the underside of the hook, the amount of the offset is just sufficient to maintain the retainer 8 in tight contact thruout its length with the staff 6. The offset 15 has the further advantage of providing a fulcrum 16 so that the free end of the wire can be pressed toward the staff and the remainder of the retainer 8 will spring away from the staff in an arc to free the flag from the staff and permit the offset to be disengaged from the hook 13. This position is shown in Fig. 3.

Further support is afforded for the flag and is particularly provided to prevent its longitudinal movement along the retainer 8. A plurality of teeth 17 are preferably struck up from the wire 8 and are adapted to pass thru the material of the flag 11 and indent slightly the wood of staff 6. The flag is thus kept from longitudinal shifting along the retainer 8 and is firmly held in the desired position.

It will be appreciated that simply by manipulating the free end of the retainer 8, it can be engaged and disengaged from the hook 13 and a flag can be readily and simply slipped into position and removed from position. There is no possibility of tearing the flag as it is supported for substantially its entire length. Furthermore the support for the flag is resilient and yields a slight amount in severe service so that danger of tearing the flag is obviated. In addition, the replacement and changing of flags is so easily effected that the staffs are economically retained rather than destroyed when the flag becomes worn out.

I claim:

1. A flag holder comprising a staff, a retainer formed of a single wire frictionally secured at one end to said staff and diverging longitudinally therefrom, means on said staff for receiving the other end of said retainer, and means struck from the retainer for preventing movement of a flag along said retainer when the retainer is in engagement with said staff.

2. A flag holder comprising a staff, a retainer reversely bent at one end, said reverse-bent end being imbedded in one end of the staff, and means attached to and adjacent the

other end of the staff for receiving the other end of the retainer.

3. A flag holder comprising a staff, a resilient retainer having one end fixed to one end of the staff and normally springing away from the staff adjacent the other end and having a bend therein toward said staff to act as a fulcrum, and a receiver on said staff to receive said retainer adjacent said bend.

4. A flag holder comprising a staff, a resilient flag retainer reversely bent at one end to engage one end of the staff and having a bend therein toward said staff and near the flag receiving portion of said retainer, and a receiver on said staff adapted to receive said retainer on the opposite side of said bend from the flag receiving portion whereby said bend acts as a fulcrum during the release of said retainer from said receiver.

In testimony whereof, I have hereunto set my hand.

STEPHEN SMITH.
